UNITED STATES PATENT OFFICE.

JULIUS J. STENSGAARD, OF WOODVILLE, WISCONSIN.

RACK FOR ASSORTING MAIL.

Application filed November 1, 1924. Serial No. 747,283.

The object of this invention is the provision of means whereby to facilitate the assorting of mail so that delivery may be properly and expeditiously effected.

5 Other objects and advantages will be apparent and suggest themselves as the nature of the invention is understood.

While the drawings illustrate an embodiment of the invention it is to be understood 10 that in adapting the same to meet different conditions and requirements, various changes in the form, proportion and minor details of construction may be resorted to without departing from the nature of the invention.

15 Referring to the accompanying drawings forming a part of the specification,

Figure 1 is a front view of a mail assorting rack embodying the invention,

Figure 2 is a side view of the rack, the 20 dotted lines showing the separator in rearward position,

Figure 3 is a rear view of the rack,

Figure 4 is a sectional view on the line 4— 25 4 of Figure 1 looking upwardly as designated by the arrows,

Figure 5 is a horizontal section on line 5—5 of Figure 1,

Figure 6 is a detail vertical section,

Figure 7 is a fragmentary vertical section— 30 al view, and

Figure 8 is a fragmentary horizontal sectional view.

Corresponding and like parts are referred to in the following description and designated in the several views of the drawings by like reference characters.

The numeral 10 denotes a floor plate from which projects a tubular standard 11 in which is adjustably fitted a stem 12 which is 40 held in the required adjusted position by means of a binding screw 13. A frame 14 has the stem 12 attached thereto and is supported thereby and includes a shelf 15 which inclines upwardly and forwardly from the bottom. The frame 14 is of rectangular 45 form and is open at the front and back. A plurality of rods 16 are disposed at the back of the frame in vertical and spaced relation and operate to strip the mail when 50 sorted from the separator as the latter is moved rearwardly. Other sets of rods 17 are disposed transversely of the frame and serve to divide the same vertically into assorting spaces as shown most clearly in Figures 5. Guide bars 18 are attached to the

sides of the frame 14 adjacent the bottom thereof and project rearwardly and support a frame 19 which is movable towards and away from the frame 14, suitable means being provided whereby to effect such 60

movement. In the preferred arrangement two sets of lazy-tongs 20 are provided and form connecting means between the frames 14 and 19, the two sets of lazy-tongs being connected by means of bars 21, said bars 65

being operable by means of a lever 22 which is pivoted at one end to one of the lazy-tongs and which is connected by means of a link 23 with the other set of lazy-tongs and in this manner both sets of lazy-tongs 70

are uniformly operated to move the frame 19 uniformly whereby it maintains a parallel relation to the frame 14 at all stages of its movement towards and away from the frame 14. The frame 19 is provided with 75

pairs of vertically disposed guide bars 24 which are attached at their ends to the upper and lower cross bars comprising the frame 19. A plurality of transverse bars 25 are mounted upon the vertically disposed 80

guide bars 24 and are movable vertically, being attached to lazy-tongs 26 which are pivoted at their lower ends to the lower cross bar of the frame 19. Bars 27 connect the end or extreme lazy-tongs 26 and 85

an operating lever 28 is pivoted at one end to one of the end lazy-tongs and a link 29 connects said lever with the other end or extreme lazy-tongs whereby to cause both lazy-tongs to move in unison. Fingers 30 90

project forwardly from the transverse bars 25 and are disposed horizontally and provide supporting means for the mail when 95

assorted. Upper and lower toggle links 31 connect the frames 14 and 19 and the toggle 100

links at each side are connected by means of a link 32 and in this manner the frame 19 is strengthened and braced at each stage of its adjustment when moved away from or towards the frame 14. The frame 19, transverse bars 25 and fingers 30 constitute a 105

separator for receiving the mail when assorted, the several pieces being placed upon the respective assorting fingers 30 and in the spaces formed by the rods 17, it being understood that each space is differently designated to receive mail for a particular location and after the mail has been assorted the lever 29 is operated to lower the transverse bar 25 after which the lever 22 is 110

operated to move the frame 19 and fingers 30 rearwardly so that the mail in the vertical spaces may drop and rest upon the bottom of the frame 14 from which it is removed ready for delivery in the usual way.

What is claimed is:—

1. In a rack of the character specified, a supporting frame, vertically disposed guide members, a plurality of transversely arranged article supports, and lazy-tongs connecting the article supports to effect simultaneous and proportionate movement thereof and maintain them in parallel relation at all stages of the movement.
2. In a rack of the character specified, a supporting frame, vertically disposed guide members, a plurality of transversely arranged article supports having elements disposed between and guided by said guide members, lazy-tongs connecting the article supports, and connecting means between sets of lazy-tongs to effect simultaneous adjustment of the lazy-tongs and the article supports connected thereby.
3. A rack of the character specified comprising an assorting frame, a movable frame adjustable forwardly and rearwardly, and transversely arranged coating article supports mounted for vertical adjustment up-

on the forwardly and rearwardly movable frame.

4. A rack of the character specified comprising a frame provided with rearwardly and transversely disposed sets of rods subdividing the frame into vertical spaces, a frame movable forwardly and rearwardly with respect to the first frame, transverse bars movable vertically on the forwardly and rearwardly movable frame, and fingers projecting from said transverse bars and between said rods and adapted to form supporting means for the articles when assorted.

5. In a rack of the character specified, a main frame subdivided into vertical spaces, a forwardly and rearwardly movable frame, lazy-tongs connecting the two frames, guide bars on the forwardly and rearwardly movable frame, transverse bars mounted upon the guide bars, lazy-tongs connecting the transverse bars, fingers projecting from the transverse bars, and upper and lower connected toggle links connecting the main frame and the forwardly and rearwardly movable frame.

In testimony whereof I affix my signature.

JULIUS J. STENSGAARD.
